UNITED STATES PATENT OFFICE.

GEORGE W. SOULE, DECEASED, LATE OF MERIDIAN, MISSISSIPPI; BY CONSTANCE G. SOULE AND CLYDE W. SOULE, EXECUTORS, OF MERIDIAN, MISSISSIPPI; AND CLYDE W. SOULE, OF MERIDIAN, MISSISSIPPI, ASSIGNORS TO SOULE STEAM FEED WORKS, A CORPORATION OF MISSISSIPPI.

STEAM ENGINE.

Application filed July 14, 1923. Serial No. 651,609.

To all whom it may concern:

Be it known that GEORGE W. SOULE, deceased, in his lifetime a citizen of the United States, and a resident of Meridian, Mississippi, and CLYDE W. SOULE, a citizen of the United States, and residing at Meridian, Mississippi, have jointly invented certain new and useful Improvements in Steam Engines; and it is declared that the following 10 is a full, clear, and exact description of the invention, such as will enable others skilled in the art to which it appertains to make and use the same.

This invention relates to improvements in 15 steam engines, and more particularly to engines in which directional rotation of the same is controlled by means of a reversing valve without the interposition of the usual reversing gear. The engine has been particularly designed for use in driving saw 20 mill carriages in small or medium size mills with limited boiler power, but the engine is capable of much wider application.

The invention has for its object to improve upon engines of the type indicated in 25 various particulars, among which may be mentioned the provision of a twin cylinder engine wherein the cylinders and frame are cast in one piece so as to provide a sturdy 30 engine and one which can be readily and economically manufactured; to so dispose the crank shaft in the engine frame as to permit direct coupling to either end thereof of the shaft or machinery to be driven; to 35 provide means in connection with the engine frame which will permit the mounting of the reversing controlling gear on one side or the other thereof in accordance with the requirements of the particular mill in which 40 the engine is to be used; to provide an improved form of directional controlling means for the engine, such means including a special arrangement of steam ports and cylinder slide valve; and to provide certain 45 other improvements as will more fully appear hereinafter, and in connection with the accompanying drawings forming part of this specification.

Referring to the drawings:

Figure 1 is a side elevation of the improved engine;

Figure 2 is a plan view of the same;

Fig. 3 is a rear end view of the engine;

Fig. 4 is a front end view of the engine; Fig. 5 is a sectional view taken on the line 55 5—5, Fig. 2;

Fig. 6 is a side elevation of the steam chest with the cover removed;

Fig. 7 is a sectional view taken on the line 60 7—7, Fig. 6;

Fig. 8 is a plan view of the valve chest with the cover removed;

Fig. 9 is a sectional view taken on the line 9—9, Fig. 8;

Fig. 10 is a sectional view taken on the line 65 10—10, Fig. 8;

Fig. 11 is a sectional view taken on the line 11—11, Fig. 7;

Fig. 12 is a diagrammatic sectional view showing the relationship between various 70 steam passages.

The improved engine is made with two cylinders arranged side by side, and cast integrally with a frame which supports the crank shaft and other mechanism of the 75 engine, the one-piece cast structure being conveniently designated the engine block, and generally designated by the numeral 1. The forward end of the frame has spaced, forwardly projecting sections 2, the ends of 80 which terminate in bearings 3, within which the crank shaft is mounted. The frame adjacent the cylinders is provided with standards or legs 4 and the crank-shaft-end of the frame is preferably cast with a drip 85 pan 5, and is also provided with standards or legs 6, the said legs 4 and 6 serving to support the engine proper in spaced relation from its foundational support.

The two engine cylinders are indicated at 90 7 and are arranged side by side in a horizontal plane. The engine frame which projects therefrom is of open construction and has upper and lower parallelly extending cross head guides 8, one set of guides for 95 each cylinder. This arrangement of cross head guides with respect to the cylinders enables the machining of the cross head guides by the same tool which bores out the cylinders, and a very material saving both 100 in time and labor is thereby effected, as will be readily appreciated by those skilled in the art.

The outer ends of the cylinder are provided with the usual heads 9, and which are secured to the cylinders in any suitable man-

ner, as by cap screws 10. In order to enable the front cylinder head to be positioned and secured, the engine frame in front of the cross head guides 8 is provided with an enlarged opening 11, through which the front cylinder head may be passed. The front cylinder head is indicated at 12, and is preferably screwed into the cylinder as indicated at 13, the head being provided with 10 the usual stuffing box 14.

The piston rod is indicated at 15, the piston head at 16, the cross head at 17 and the connecting rod at 18, these parts being of more or less conventional construction. The 15 crank shaft is indicated at 19 and the connecting rod 18 is connected thereto by suitable bearings 20. Any suitable or preferred type of oiling system may be employed, oil cups 21 being shown for convenience in illustration.

The cylinders are provided with steam chests 23 at their lateral sides in such a manner that the valve seats lie in planes transverse to the horizontal.

25 Referring to Fig. 7, numerals 24 indicate a pair of communicating steam ports, which may serve as conduits for live steam or exhaust steam, depending upon the directional rotation of the engine, as will hereinafter 30 be fully explained. The steam ports which lead to the respective ends of the individual cylinders, are indicated at 25, and these serve alternately as conduits for the admission of live steam into the cylinder in one 35 direction of the movement of the piston and as conduits for the exhaust steam on the return movement of the piston, as will be readily understood.

Between the conduits or ports 25 is a port 40 26, which is similar to the ports 24, that is to say, the port 26 will serve as a conduit for live steam or as an exhaust port, depending upon the directional rotation of the engine determined by the position of the 45 reversing valve, hereinafter more fully described. The slide valve which co-operates with the said ports is indicated at 27, and the valve stem thereof at 28. The back of the valve 27 is provided with spaced 50 seats or saddles 27', within which the valve stem 28 is received, and the latter is confined against longitudinal movement with respect to the valve by means of set collars 29 on the valve stem, said collars permitting 55 relative adjustment between the valve stem and its valve, as will be readily understood. The outer end of the valve stem is slidably received within the socket bearing 23' of the steam chest casing 23. The cover plate of 60 the steam chest is indicated at 30 and is retained thereon in any suitable manner by cap screws 31. The stuffing box (the packing and nut not shown) through which the valve stem passes is indicated at 32, which 65 latter is, of course, aligned with the socket

bearing 23 at the opposite end of the steam chest.

In order to provide for the more effectual seating of the valve 27 on the seat, there is provided a spring S, which is arranged between the valve 27 and the stem 28 therefor, the spring being conveniently made from spring wire, which intermediate its ends is looped about the valve stem 28, and has its free ends positioned in a shallow 75 channel in the back of the valve. This manner of positioning the ends of the spring in the channel serves to prevent displacement of the spring along the valve stem. The spring S may be relatively light for 80 reasons which will more fully appear hereinafter.

The end of the valve stems adjacent the stuffing box are provided with knuckles 33, which are connected to valve rods 34, which 85 in turn are connected to individual eccentrics 35, preferably cast integrally with the crank shaft and being arranged at an angle of 90° with respect to the adjacent crank of the crank shaft, it being understood that there is an eccentric for each crank of the crank shaft, or in other words, for each cylinder.

It will be noted that the ends of the crank shaft extend beyond its supporting bearings 3 in the engine frame for some considerable distance, and that the eccentrics 35 are disposed on the outer sides of the said bearings 3. The terminal ends of the crank shaft 19 are tapered as at 36, in order to 100 facilitate the direct coupling of the crank shaft to a shaft or other mechanism to be driven. Both ends of the crank shaft are tapered as said to permit coupling to be made at either end of the same depending upon the conditions in the mill in which the engine is to be used. The crank shaft is preferably a cast member suitably cored. The crank shaft is cast with drum-like members 37 between the cranks and on either 110 side thereof, and within these drums may be deposited heavy metal for counterbalancing the crank shaft.

The reversing valve for the engine is contained within the steam chest 38, located on 115 top of the engine cylinders. The live steam pipe which leads to the reversing valve steam chest is indicated at 46, the cover plate of the chest being indicated at 44 and shown as secured thereto by means of cap screws 120 45. The reversing valve is a D-valve as indicated at 41, and on its back, has a U-shaped saddle within which is received a valve stem 42, the latter being confined against longitudinal movement with respect 125 to the valve by means of set collars 43 affixed to the rod 42 on either side of the saddle, as will be readily understood. The valve rod 42 passes through a suitable stuffing box 47 (the nut and packing therefor 130

not shown) and is connected to control mechanism hereinafter specified.

The reversing valve 41 co-operates with three ports, 24', 26' and 40, and is of a size to completely cover these ports at one time. When the reversing valve 41 is moved to open the port 24' to the admission of live steam from the steam pipe 46, steam will flow through said port 24' to the ports 24 in the steam chest for the respective cylinders, it being remembered that the ports 24 are in communication. It will be noted that live steam which enters the ports 24 of the cylinder steam chest, meets the side of the slide valve 27. Referring to Fig. 7, and assuming that the slide valve 27 is moved to the right, steam will enter the front steam port 25 at the left of Fig. 7 and enter the cylinder and exert its expansive force against the piston, which will thereupon move toward the right. Steam from the other side of the piston at this time is being exhausted through the other port 25 and into the port 26, this port being in communication with the port 26' in the reversing valve steam chest, by reason of the reversing valve 41 having been moved to the right, it being in communication with the port 40 in said reversing valve steam chest, the port 40 being in communication with the exhaust pipe 60 (see Figs. 1, 2 and 3) which is appropriately connected to the reversing valve steam chest. As long as the reversing valve 41 remains in position to allow the port 24' to be opened to live steam, the slide valve 27 will move back and forth to admit steam from the ports 24 into the ports 25, and the engine will run in a given direction, as will be readily appreciated.

Assuming that it is desired to cause the engine to rotate in the opposite direction from that above indicated, the reversing valve 41 will be moved to close the port 24' and to open the port 26' to live steam. Inasmuch as the port 24' is now closed to live steam, it follows that no live steam will flow to the ports 24 in the cylinder steam chest. It will also be observed that the port 24' will be in open communication with the port 40 in the reversing valve steam chest. It will be further remembered that the port 26' in the reversing valve steam chest is in direct communication with the port 26 in the cylinder steam chest, and consequently live steam will flow to the port 26 when the reversing valve is in the last named position.

Again assuming that the engine cylinder slide valve 27 is at the right in Fig. 7, live steam will flow from the port 26 to the port 25 at the right of the said port 26, with the result that the steam will enter the cylinder between the piston and the front cylinder head 12. It will be recalled that when live steam was admitted to the ports 24, that the

steam entered the port 25 at the left of Fig. 7, whereby steam was entered into the cylinder between the back cylinder head 9 and the piston. As long as the live steam is permitted to flow into the port 26, the engine will continue to rotate in its new direction. When the slide valve 27 moves to the left in its normal cycle of operation, the port 25 at the right of the port 26 will be closed to live steam and brought into communication with the port 24 at the right of the port 26. It will be recalled that the port 24 is in communication with the port 24' in the reversing valve steam chest, and that this latter port is closed against live steam and is in open communication with the port 40, which latter is in communication with the exhaust pipe, as has already been indicated. Referring to Fig. 5, reference characters 24^a indicate a continuation of the ports 24 and 24', and reference character 26^a indicates a continuation of the ports 26 and 26'.

It will now be seen that the direction of rotation of the engine is controlled by the reversing valve by admitting live steam into one or the other of the ports 24' or 26', and that whether or not the ports 24 and 26 serve as ports for live steam or as exhaust ports depends upon the positioning of the reversing valve 41.

It has been pointed out that a spring S is preferably employed in connection with the slide valves to hold them to their seats. Inasmuch as the live steam does not enter the steam chest in a manner to exert pressure on top of the slide valves, as is the usual practice in steam engine construction, means are provided in addition to the spring S to hold the slide valves to their seats, such means including a port 61 through the slide valve through which steam may pass, and exert pressure upon the exterior of the valve. A check valve, preferably in the form of a ball 62 (Fig. 11) is placed in the port 61 to prevent return of steam under pressure from the back of the valve. When the port 26 is supplying live steam, some of the steam will enter the port 61 and find its way into the steam chest and exert pressure to hold the valve to its seat. When the ports 24 are the live steam ports, it is found that the steam which is being exhausted through the port 26 will pass through the port sufficient to exert sufficient pressure on the back of the valve to hold the same to its seat, it being remembered that the check valve 62 will prevent the return of steam from the steam chest through the port 61. Also any steam that may escape from the ports 24 and into the steam chest will assist in holding the valve to its seat. In any event, it is found that the spring S in connection with the arrangement just specified, is sufficient to hold a valve in proper functioning position.

It may also be pointed out that inasmuch

as the slide valves have their faces arranged in substantially vertical planes, it is desirable to provide a bearing 22^a at the lower edge of the slide valve, this bearing having an appropriate seat at the lower end of the steam chest, as will be readily understood.

- It has been pointed out how the directional rotation of the engine may be controlled by the reversing valve. It will be remembered 10 that the engine is primarily designed for operating carriages in saw mills. The operator who is controlling the engine to move the carriage, finds it highly desirable to have the carriage travel in the same direction in 15 which the engine-controlling lever is moved. That is to say, if the lever which controls the engine is moved to the right, it is desirable that the carriage shall move toward the right and vice versa. In order to allow 20 the engine to be readily adapted to this condition, there is provided between the reversing valve and the controlling lever therefor, a lever arrangement which will enable the directional rotation of the engine to be 25 set as desired.

Referring more particularly to Fig. 2, it will be seen that the stem 42 of the reversing valve projects beyond the stuffing box some distance. Operatively connected with the 30 valve stem 42 is a lever 48, which is anchored at one end to a post 50, which is screwed into a boss 49. This lever 48 is adapted to be controlled by a main controlling member 55, which projects upward from a rock 35 shaft 54, which is mounted at one of its ends on a boss 53, which projects from the engine frame.

Projecting from the rock shaft 54 is a 40 crank arm 56, to which is connected by means of a pin 58, a rod 57, which extends toward and is connected to the lever 48, there being a short section of link between the lever 48 and the rod 57. It will now 45 be readily appreciated that the reversing valve can be controlled by proper manipulation of the controlling lever 55. If the assembly as shown in Fig. 2 does not give the desired directional rotation to the engine for a certain swinging movement of the control lever 55, it is only necessary to change 50 the lever 48 from a lever of the first class to a lever of the second class. In order to effect this change, there is provided an additional boss 49' on the other side of the valve stem 42 to permit the removal of the fulcrum post 50 from the boss 49 to the boss 49'. When the fulcrum post 50 has been positioned at the boss 49', the lever 48 will be 55 positioned in such a manner that the end 48' thereof will be connected to the valve stem 42 and the intermediate joint 48^a will be fulcrumed or connected to the post 50. The lever 48 is provided with an extra opening 51 so that the link 52 can be connected to 60 the opening 51. By thus converting the 65

lever 48 into a second class lever instead of a first class lever as shown in Fig. 2, means have been provided for moving the reversing valve in one direction or another with respect to the control lever.

It will be noted by reference to Fig. 2 that a pair of bosses 53 is provided, one on each side of the engine frame, and that the terminal ends of the same are tapered. The provision of a pair of bosses is desirable in order to allow the controlling lever 55 to be positioned on one side or the other of the engine. It will, of course, be understood that the lever 48, which connects directly to the reversing valve, will be appropriately disposed depending upon what side of the engine the controlling lever 55 is to be placed. The bosses 53 are tapered so as to permit the rock shaft 54 to be readily positioned thereon. The rock shaft 54 is preferably a whole tube, as a piece of pipe, such as may be found about the mill where the engine is to be used. The pipe which is to constitute the rock shaft is slipped over the tapered part of the lug 53 and so positioned 90 thereon as to have a free rocking fit. The other end of the pipe or rock shaft will be positioned in a suitable bearing (not shown) of any desired form.

It may be pointed out that a convenient form of connection between the lever 48 and the valve stem 42 includes a pair of set collars 42' affixed to the stem 42 on either side of said lever. The lever 48 is preferably yoked, as shown in Fig. 3, to receive the 100 valve stem 42 and to receive the post 50.

Suitable means to provide for the taking up of wear between the various parts of the reversing controlling mechanism are preferably provided at the joints, and such means between the fulcrum post 50 and the lever 48 may conveniently take the form of a hexagonal nut 50', which will be screwed on to the post 50, the nut having diametral recesses or a hole passing therethrough for the reception of pivot screws 50^a, which will be screwed into the side bars of the yoke of the lever 48. A similar connection may be used between the lever 48 and the valve 110 stem 42.

From the foregoing description, it will be apparent that there has been provided a twin engine which while particularly adapted to a special use, is nevertheless well adapted to various uses and which is simple 120 in construction and not liable to get out of order. While the invention has been described with considerable particularity of detail, it is to be distinctly understood that no limitations are intended except as may 125 be imposed by the appended claim.

What is claimed is:

In a steam engine, means for reversing the directional rotation of the engine comprising a reversing valve for controlling two 130

independent steam ports, a control lever mounted at a point remote from the reversing valve, means between the control lever and the reversing valve for moving the said valve by the control lever, said means including a lever of the first class connected to the reversing valve, said first class lever provided with means permitting the same to be changed into a lever of a different class to permit the reversing valve to be moved in

an opposite direction having given movement of the control lever.

In testimony whereof we hereunto affix our signatures.

CONSTANCE G. SOULE,

CLYDE W. SOULE,

Executors of the Estate of George W. Soule, deceased.

CLYDE W. SOULE.
